UNITED STATES PATENT OFFICE

RUDOLPH M. SANDERS, OF NEW YORK, N. Y., ASSIGNOR TO ADARTCRAFT, INC., OF NEW YORK, N. Y., A CORPORATION OF DELAWARE

DISPLAY DEVICE

Application filed June 2, 1931. Serial No. 541,612.

This invention relates to display devices and more particularly to display devices for use in connection with merchandise sold in packages, such as cigarettes. One type of package in which cigarettes are sold is a suitably lithographed paper package containing twenty cigarettes. These packages are packed in cartons containing ten packages in two rows of five each so that when the carton is opened for display a row of five packages of cigarettes is visible. For display purposes a dummy consisting of a flat sheet having the representation of the front of five packages of cigarettes has heretofore been employed. Several brands of cigarettes packed in this manner are now provided with an outer covering of cellophane or other transparent wrapping and the use of a dummy in the form of a flat sheet is no longer satisfactory for displaying cigarettes packed in this manner.

In the present invention I provide a display device which may be inserted in a carton to create the appearance of a full carton of cigarettes in which the packages are provided with coverings of transparent material, or the invention may be applied directly to the top of a dummy carton which is now employed for display purposes and in which the top of the carton is provided with representations of individual packages.

In one form of the invention I employ a sheet of cardboard of the same size as the carton and provided with flanges or other means for supporting it in the position normally occupied by the top surfaces of the upper row of packages when the carton is full. The surface of the sheet is lithographed, or provided with labels representing the exposed portions of the five packages of cigarettes normally packed in the top row of the carton. A slot is formed in the sheet between each pair of package representations and I place a sheet of transparent material, such as cellophane, over the cardboard sheet and extend it into each of the slots. The edges of the slots may be rounded to simulate the side edges of cigarette packages, and with the sheet of cellophane or other transparent material extending over these rounded edges,

the display device produces the effect of a full carton of cigarettes.

In applying the invention to a dummy carton having the representations of five packages of cigarettes on its top surface, the surface of the carton is slotted between each pair of package representations and a sheet of cellophane or other transparent material is placed over the surface and tucked into the slots. In this form of the invention the edges of the slots may also be rounded to more fully bring out the representation of the cigarette packages.

In the accompanying drawings I have shown several forms of the invention. In this showing,

Fig. 1 is a perspective view of the display member adapted to be inserted in a carton, with a portion of the cellophane sheet broken away;

Fig. 2 is a similar view of the display member in an inverted position;

Fig. 3 is a similar view of a carton showing the display member arranged therein;

Fig. 4 is a vertical, transverse, sectional view of the display member showing the sheet of cellophane positioned thereon in the course of assembly;

Fig. 5 is a plan view of a dummy carton blank showing the invention applied thereto;

Fig. 6 is a perspective view of the dummy carton assembled;

Fig. 7 is a detailed, sectional view showing the arrangement of the cellophane in the slots; and

Fig. 8 is a detailed, sectional view of one end of the carton in assembled position substantially on line 8-8 of Fig. 6.

Referring to Figs. 1 to 4 of the drawings the reference numeral 1 designates generally a display device consisting of an upper surface which is divided into a plurality of representations of the top surfaces of individual packages as indicated at 2. As shown, the display device is of a proper size to simulate five packages of cigarettes but it will be apparent that the number of packages simulated is not a feature of the invention and that the illustration is used due to the fact that cigarette packages are packed in cartons

with five packages in each row. In displaying other merchandise the number of packages simulated would be varied according to the manner in which the particular merchandise is packed. At the front and back of the display device I provide flanges 3 which correspond to the bottom and top edges of cigarette packages arranged in the carton. The surfaces of the individual package representations may be suitably lithographed or labels may be arranged thereon showing the name of the brand as indicated at 4 and any other symbol or advertising matter appearing on the cigarette package as indicated at 5. The portion of a revenue stamp appearing at the upper edge of the front surface of the package may be simulated as indicated at 6. Between each pair of individual package representations I provide a slot 7 and this slot preferably extends down the flanges a slight distance as indicated at 8. The edges of the slot may be rounded downwardly to more closely simulate the shape of the conventional cigarette package of this character. A sheet 9 of cellophane or other suitable transparent material is adapted to be arranged over the display device and extends into the slots 7. As shown in Fig. 4 of the drawings, the sheet is of greater width than the width of the display device and is adapted to be arranged on top of the display device and then tucked into each of the slots 8, as indicated at 10. Within the slots the loops 10 may be flattened against the under surface of the display device and secured thereto in any suitable manner as indicated in Fig. 2 of the drawings. The cellophane sheet is longer than the display device and is folded over the edges and secured to the under surfaces as indicated at 11 in Figs. 1 and 2 of the drawings. When the loops 10 are inserted in the slots 8, an excess of material is formed in the portion 12 of the cellophane which covers the flanges 3. As shown in Figs. 1 and 2 of the drawings, this portion may be folded over to form loops 13 and secured to the adjacent surface of the cellophane. By extending the slots slightly below the surface as indicated at 8, the loops 13 are sufficiently below the surface that they are not visible when the display device is placed in a carton. In Fig. 3 of the drawings the display device is illustrated in position in a carton of conventional construction. It will be noted that the depth of the flanges 3 is such that the surface of the display device is in the plane normally occupied by the surfaces of the packages of cigarettes in the top row of a carton. With the cellophane sheet 9 tucked in the slots 8, extended over the ends of the display device as at 11, and with the excess width of the cellophane sheet extending downwardly over the flanges 3 at the front and back of the carton, a cellophane covered surface is visible at all points and the illusion is created of a pack-

age of cigarettes entirely wrapped in cellophane. The display device may therefore be used for window displays and the like without the necessity of exposing full cartons of cigarettes.

In Figs. 5 to 8 of the drawings I have illustrated the application of the invention to a dummy carton that has heretofore been used in the display of cigarettes. As shown in Fig. 5 of the drawings, the carton consists of a bottom 15, front and rear walls 16 and 17 and an upper surface 18. It is scored along lines connecting these walls to permit folding into the form shown in Fig. 6 of the drawings. As shown, the rear wall is provided with a flange or extension 19 and the upper surface is provided with a similar flange or extension 20. When the carton is assembled the under surfaces of these two walls are provided with a suitable adhesive and are adapted to be secured to each other extending substantially vertically. A dummy lid 21 (see Fig. 6) may then be secured to the front surface of the flange or extension 20 by a suitable adhesive, or in any other manner.

On the surface 18 I provide a plurality of representations of individual packages 22 and these representations may be provided with the name of the brand, trademark or other pictorial representation and revenue stamps as described in connection with Fig. 1. The whole is formed by lithographing or by pasting labels to this surface, or in any other suitable manner. The desired result is to obtain the appearance of individual packages of cigarettes. Between each pair of individual representations I provide a transverse slot 23 and at the front and back edges of this surface of the carton I provide slots 24 extending at right angles to the slots 23. The provision of these secondary slots permits the edges of the individual representations to be slightly rounded to more closely simulate a package of cigarettes and also facilitates arranging cellophane or other transparent material in the slots. A sheet 25 of cellophane or other transparent material (see Figs. 7 and 8) of the same width as the upper surface of the carton is then arranged over this upper surface and tucked into the slots 24 to form loops 26 as indicated in Fig. 7 of the drawings. After the sheet is in position the loops may be flattened as shown in Fig. 8. At each end of the top surface 22 of the dummy carton I provide end flaps 27 and the length of the cellophane sheet is sufficient to permit the ends of the sheet to extend over these flaps as indicated at 28 in Fig. 8 of the drawings. The arrangement of the loops in the slots 23 and the extension of the ends of the cellophane sheet over the flaps 27 gives the appearance of separate wrappings of cellophane on each of the individual packages.

In constructing the carton I slightly modify

fy the end flaps of the dummy carton here-
tofore employed in order to permit the ar-
rangement of the cellophane over the end
flaps 27 and within the ends of the package.
5 In addition to the flaps 27 carried by the up-
per surface of the carton, the front and back
walls are provided with flaps 29 and the bot-
tom wall is provided with a flap 30 scored
10 along a line 31 to permit folding of the end
portion 32. In assembling the carton the
flap 27 with the cellophane covering is placed
on the inside, the flaps 29 placed next to the
flap 27 and the flap 30 is then folded inwardly
15 on the line 31 with the end portion 32 ex-
tending downwardly inside of the body of
the flap and secured to the flaps 29 by an
adhesive or in any other suitable manner.

In each of the forms of the invention de-
scribed a very realistic representation of a
20 carton of cigarette packages in which the in-
dividual packages are provided with a trans-
parent covering is obtained and either of the
forms may be used for display or advertis-
ing in lieu of full cartons of cigarettes or
25 in lieu of devices of the same general char-
acter which have heretofore been employed
but which do not produce the appearance of
packages provided with transparent wrap-
pings.

30 I claim:

1. A display device comprising a member
formed to simulate a plurality of individual
packages, said member being provided with
relatively narrow slots between adjacent
25 package representations, and a sheet of
transparent wrapping material arranged
over said member and extending into said
slots.

2. A display device comprising a member
40 formed to simulate a plurality of individual
packages, said member being provided with
relatively narrow slots between adjacent
package representations, the edges of said
slots being rounded, and a sheet of transpar-
45 ent wrapping material arranged over said
member and extending into said slots.

3. A display device comprising a member
50 formed to simulate a plurality of individual
packages, said member being provided with
slots between adjacent package representa-
tions, and a sheet of transparent wrapping
material arranged over said member and ex-
55 tends into said slots, the portions of said
sheet within said slots forming loops, said
loops being flattened.

4. A display device comprising a member
formed to simulate a plurality of individual
packages, said member being provided with
60 slots between adjacent package representa-
tions, and a sheet of transparent wrapping
material arranged over said member and ex-
tends into said slots, the ends of said sheet
being extended over the ends of said member.

5. A display device comprising a sheet
65 folded to provide an upper surface and de-

pending flanges, the upper surface being
formed to simulate a plurality of individual
packages, said member being provided with
slots between adjacent package representa-
70 tions, said slots extending beneath the upper
surface of said member into said flanges, and
a sheet of transparent wrapping material of
greater width than said upper surface ar-
ranged on said member and extending over
75 said flanges and tucked into said slots.

6. A display device comprising a surface
simulating a plurality of individual pack-
ages, said surface being provided with slots
between adjacent package representations
80 and being provided with slots at right angles
to said first mentioned slots at the ends of
said first mentioned slots, and a sheet of
transparent wrapping material of the same
width as said surface arranged on said sur-
85 face and tucked into said slots.

7. A display device comprising a carton
having its upper surface formed to simulate a
plurality of individual packages, said surface
being provided with slots extending trans-
versely of said surface between adjacent
90 package representations, said surface being
further provided with spaced slots at the
front and back edges thereof at right angles
to said first mentioned slots and intersecting
said first mentioned slots, and a sheet of
95 transparent wrapping material of substan-
tially the same width as said surface ar-
ranged thereon and tucked into said first
mentioned slots.

In testimony whereof I affix my signature. 100
RUDOLPH M. SANDERS.
